UNITED STATES PATENT OFFICE.

PETER A. WALLER, OF KEWANEE, ILLINOIS, ASSIGNOR TO BOSS MANUFACTURING COMPANY, OF KEWANEE, ILLINOIS, A CORPORATION OF ILLINOIS.

GLOVE.

1,103,021.

Specification of Letters Patent. Patented July 14, 1914.

Application filed November 9, 1910. Serial No. 591,507.

To all whom it may concern:

Be it known that I, PETER A. WALLER, a citizen of the United States, residing at Kewanee, in the county of Henry and State of Illinois, have invented certain new and useful Improvements in Gloves, of which the following is a specification, reference being had therein to the accompanying drawing.

10 This invention relates to an improvement in gloves and more particularly to the class of gloves which are formed of heavy fabric and are used to a large extent by workmen.

One of the objects of the present invention is the provision of a glove of this character which will fit the hand more snugly and will be less bunglesome than the gloves of this kind now in use.

A further object of the invention is the provision of a glove of this character which is so formed that the seams are located in positions so that they will not be subjected to excessive strains and will not chafe the hand of the wearer of the glove.

20 Other objects of the invention will be apparent from the detailed description hereinafter when read in connection with the accompanying drawings forming a part hereof, wherein a convenient embodiment of the invention is illustrated and wherein like numerals of reference refer to similar parts in the several views.

In the drawings, Figure 1 is a front view of a glove embodying the present invention, Fig. 2 is a rear view thereof, Fig. 3 is a diagram of the blank for the front of the glove, Fig. 4 is a diagram of the blank for the back of the glove, Fig. 5 is a diagram of the blank for the upper portion of the thumb of the glove, and Fig. 6 is a diagram of the blanks for the fronts of the middle fingers of the glove.

Referring now more particularly to the drawings, A designates the blank for the front pieces of the glove which is formed of a single piece of inelastic fabric such as is usually employed for gloves of this character and comprises a palm piece 1, a downwardly extending thumb member 2, which is positioned at one side of the palm piece 1 and is adapted when the portions of the glove are assembled to form the inner side of the thumb of the glove, and finger sections 3 and 4 which project upwardly from the thumb piece 1 of the blank and are

adapted to form the front and sides of the first and fourth fingers of the glove. Downwardly curved slits extend inwardly into the body of the finger A from the inner edges of the finger pieces 3 and 4 at the base thereof to form flaps 3^a and 4^a at the inner sides of the said finger pieces, which flaps are of sufficient width to, when the sections of the glove are assembled, extend between the fingers of the wearer of the glove and over upon the backs thereof. A flap 3^b is also formed along the outer edge of the finger section 3 which is adapted to be folded rearwardly. A blank 5 is provided which is preferably of elastic material although, if desired it may be made of inelastic material as the blank A and the upper portion of which is formed so as to cooperate with the thumb section 2 heretofore referred to, to form the thumb of the glove and the lower section of which is adapted to be secured in the palm piece 1 of the glove and to constitute a covering for that portion of the hand adjacent the base of the thumb. Sections 6 and 7 are provided which are preferably formed of the same inelastic material as the blank A and which are adapted, when the sections of the glove are assembled, to constitute the fronts and sides of the middle fingers of the glove, such sections being of sufficient width that the edges thereof will lie upon the backs of the middle fingers of the wearer of the glove. The lower edges of the finger pieces 6 and 7 are straight for substantially the greater portion of their width and terminate at one end in upwardly inclined portions 6^a and 7^a.

B designates the blank of the back of the glove, which blank is formed from a single piece of any suitable elastic material and comprises a portion which is adapted to constitute the back proper of the glove and finger portions 9, 10, 11 and 12 which are adapted to constitute the backs of the fingers of the glove.

To form the glove, the thumb section 2 of the blank A is folded to an upright position and the thumb member 5 is stitched thereto and to the adjacent portion of the palm piece 1 of the blank A. The flaps 3^b, 3^a and 4^a of the finger pieces 3 and 4 are folded rearwardly. The upwardly inclined portions 6^a and 7^a of the finger sections 6 and 7 are stitched together, thus forming a straight seam between the fingers, and the

100

105

110

central portions of the bases of said finger sections are stitched to the curved edge of the blank A which is positioned between the finger sections 3 and 4 thereof, and the remaining portions of the bases of the finger pieces 6 and 7 are then stitched to the lower curved edges of the flaps 3^a and 4^a. The elastic back is then secured to the front of the glove by stitching the edges thereof to the edges of the inelastic portion of the glove and by stitching the edges of the finger portions thereof to the edges of the fingers of the front portion of the glove. Inasmuch as the inelastic portions of the fingers of the glove are of such a width that they form the fronts and sides of the fingers and that they are adapted to not only extend between the fingers but also to lie upon the backs of the fingers, it will be seen that the seams which unite the elastic backing to the remainder of the glove will all be positioned upon the backs of the fingers of the wearer, so that not only will such seams be protected from wear, but they will also be so positioned that they in no way interfere with the free manipulation of the hand of the wearer of the glove. The only finger seam which is positioned at the front of the glove is that at the base of the middle fingers and by locating the same at this point it will be obvious that it is practically relieved from all strain when the hand of the wearer is closed or partly closed, as when grasping or holding an object. By providing a glove of this character with a one-piece elastic back and fingers the glove adjusts itself to different sized hands and fits much more snugly than the ordinary working glove, thus enabling the workman to work much faster and more skilfully than is possible with the gloves of this kind heretofore in use.

The lower portion of the glove is provided with a wrist band C which may be of any well known type.

While a convenient embodiment of the invention is illustrated in the accompanying drawings, it will be obvious that many changes may be made to the form and con-

struction herein shown without departing from the spirit of the invention as defined in the accompanying claim.

I claim:—

A glove consisting of a blank of inelastic material constituting a palm portion the wrist edge and the sides of the blank being substantially straight, a front thumb section at one side of the blank adjacent its wrist edge, said thumb section extending downwardly toward the wrist edge and outwardly beyond the adjacent side edge of the blank whereby the same may be folded to an upright position, the blank having formed at its edge remote from its wrist edge separate spaced finger portions adapted to form the front and sides of the first and fourth fingers of the glove; said finger portions being of a width to extend between the fingers of the wearer and lie upon the backs thereof, a pair of separate inelastic finger pieces secured at their lower edges to the portion of the blank intermediate the integral finger pieces thereof and to the adjacent lower edges of said finger pieces, a separate thumb section formed of a single piece of material and arranged to extend at the front of the glove to completely cover the back of the thumb and the fleshy part of the hand of the wearer adjacent the base of the thumb, the section being secured at its upper edges to the front thumb piece and having its lower part secured to the inelastic palm piece, and a one piece back for the glove of elastic material comprising a back proper and finger backs, the back proper having a straight wrist edge and straight side edges, the side edge which is disposed adjacent the thumb being recessed adjacent the wrist edge, said back piece being secured at its edges to the various other members which constitute the glove.

In testimony whereof I affix my signature in presence of two witnesses.

PETER A. WALLER.
